(57) **CLAIM**

The ornamental design for a book with provision for at least one moveable object implanted therein, as shown and described.

DESCRIPTION

FIG. 1 is a perspective view of a book with provision for at least one moveable object implanted therein showing the invention, the book being shown in a closed position; FIG. 2 is a front view of the invention; FIG. 3 is a right side view of the invention; FIG. 4 is a rear view of the invention; FIG. 5 is a left side view of the invention; FIG. 6 is a top or bottom view of the invention; and, FIG. 7 is a second perspective view of the invention with the book in an open position.

The broken lines defining the boundaries of the at least one moveable object are shown for illustrative purposes only and form no part of the claimed design.
